E. N. Roland,

Lubricator.

N° 18,863.

Patented Dec. 15, 1857.

UNITED STATES PATENT OFFICE.

ENOCH N. ROLAND, OF BALTIMORE, MARYLAND.

IMPROVEMENT IN LUBRICATING-OIL CUPS.

Specification forming part of Letters Patent No. 18,863, dated December 15, 1857.

To all whom it may concern:

Be it known that I, ENOCH N. ROLAND, of the city and county of Baltimore and State of Maryland, have invented an Improved Oil-Cup for Steam-Engines; and I do hereby declare that the following is a full and exact description thereof, reference being had to the accompanying drawings making a part of this specification.

Figure 1 is a top view of said oil-cup; and Figs. 2, 3, and 4 vertical sections of the same, representing the respective parts thereof in different positions.

Similar letters indicate like parts in each drawing.

The body of my improved oil-cup is composed of the sections A B, which are united to each other by means of a central screw-joint.

A couple of screw-actuated valves are combined with each other and with the sections of my improved oil-cup in the manner represented in the accompanying drawings.

The neck, which rises from the section A of my improved oil-cup, terminates in a funnel or funnel-shaped cup, and a screw-thread is formed within an enlarged portion of the aperture in said neck. A cross-bar *h*, which is combined with the lower extremity of the said section A, has a vertical screw-aperture formed within the center of the same.

The perforated screw-neck *g*, which descends from the lower extremity of the section B of the aforesaid oil-cup, enables the said cup to be conveniently combined with a steam-engine.

One, two, or more vertical grooves *f* are formed in the sides of the screw portion of the aperture within the neck of the section A of my improved oil-cup, which groove or grooves may descend nearly to the shoulder *i* at the bottom of the screw portion of the aperture in said neck.

The screw-valve *b* fits accurately into the screw-aperture within the neck A of my improved oil-cup, and the screw-shank of the valve *d* works accurately within a central screw-aperture in the said valve *b*, and also within the screw-aperture in the cross-bar *h*. The lower extremity of the valve *b* is of such a shape that it fits accurately to the shoulder *i* when it is turned down to its lowest position, and the face of the valve *d* is of

such a shape that it perfectly closes the aperture in the neck *g*, which descends from the lower section B of the oil-cup.

The usual position of the valves of my improved oil-cup is represented by Fig. 2. The said oil-cup having been combined with a steam-engine, the piston of said engine is supplied with oil in the following manner, viz: The valve *b* must first be unscrewed to such a degree as to bring its seat above the lower ends of the grooves *f f*, as shown in Fig. 4, and then oil or melted tallow poured into the funnel *e* will flow freely into the interior of the oil-cup. As soon as a sufficient quantity of oil or tallow has been conveyed into the body of the oil-cup the valve *b* must be screwed down again so firmly as to cut off all communication between the interior of the oil-cup and the funnel *e*; then, by elevating the valve *d*, as shown in Fig. 3, the oil or tallow will pass freely into the cylinder of the steam-engine without allowing the steam to escape from said engine, with the exception of the small quantity which will pass into the body of the oil-cup. Before the oil-cup is again charged with oil the valve *d* must be again screwed down to the position represented in Fig. 4.

The valve *b* is operated by means of the crank *j*, and the valve *d* is operated by means of the crank *k*.

Cold tallow may be placed within the funnel *e*, for the purpose of being melted preparatory to its being conveyed into the body of the oil-cup and thence into the cylinder of the steam-engine.

Having thus fully described the construction and operation of my improved oil-cup for steam-engines, what I claim therein as new, and desire to secure by Letters Patent, is—

The peculiar combination of the screw-valves *b d* with each other, and with the funnel, neck, and other portions of said oil-cup, substantially as herein set forth.

The above specification of my new and improved oil-cup signed this 8th day of September, 1857.

ENOCH N. ROLAND.
